TYPEWRITING MACHINE

William F. Helmond, West Hartford, Conn., assignor to Underwood Elliott Fisher Company, New York, N. Y., a corporation of Delaware

Application January 23, 1935, Serial No. 3,037

7 Claims. (Cl. 197—114)

This invention relates to typewriter-carriage mechanism, and aims to provide for quiet operation thereof, and to gain other advantages, by means of certain novel devices which will be simple so as to conduce to economical manufacturing and servicing, and which will nevertheless be fully effective and durable in use.

A feature of improvement pertaining to quiet and non-jarring operation resides in having the usual line-space-lever-nose engage the line-space-pawl carrier, by means of a yieldable element which is arranged to act as an anti-rattle and buffer device, and which may be inexpensively made, and used with existing designs of line-space levers, such as the Underwood.

Another feature of improvement is contrived by arranging a part which forms a spring for the line-space pawl to also serve, at practically negligible extra cost, as a resilient stop-device for quietly arresting the spring-pressed return of the line-space-pawl carrier.

Another feature of improvement pertains to quietly arresting the escape of the limber-dog of the letter-feed escapement, and for this purpose a novel reflexed leaf-spring is provided, and said spring may moreover be adjustably secured to the dog-rocker by but one screw, inasmuch as it may be provided with an anchoring tongue spaced from said one screw and made to engage a kerf usually provided on the dog-rocker.

An oblong ferrule-like resilient ring, used to arrest the case-shifts quietly, has one long side inserted edgewise in a slot of a supporting boss to extend from the latter cantilever-wise, so that the boss-overhanging end of the oblong ferrule may quietly arrest the case-shifts. According to the present improvements, said ferrule-retaining slot may extend perpendicularly to the case-shift direction. The other long side of the ferrule, outside of the boss, is parallel to the plane of the slot, and presents the stop-face for the lower-case platen-position.

The boss-overhanging part of the long ferrule-side retained in said slot presents the stop-face for the upper-case platen-position and is inclined, by means of a bend in said long side, relatively to said slot, so that endwise adjustment of the ferrule along the slot effects adjustment of said upper-case position. Another improvement resides in means, supplemental to a ferrule-clamping screw which bears upon an edge of the ferrule, for preventing play of the ferrule in case-shifting direction in the slot, whereby the ferrule, in any endwise adjusted position, is enabled to uniformly limit the case-shift movements.

These devices may be at the front of the side-members of the platen-shifting frame. At the rear of said platen-frame side-members there may be abutment of other stop-surfaces to determine only the normal or lower case position of the platen-frame, and there are provided novel means for retaining cushioning elements for such abutment.

Other features and advantages will hereinafter appear.

In the accompanying drawings,

Figure 1 is a perspective view illustrating details of the case-shift cushioning devices at the rear of the platen-shifting frame.

Figure 2 is a sectional view of a portion of the parts of the case-shift stop-devices at the front of the platen-frame.

Figure 3 is a perspective view of a typewriter-carriage such as the Underwood, and shows in perspective the means including the present improvements.

Figure 4 is a perspective view of the escapement-mechanism illustrating details of the novel means for quietly arresting the limber-dog.

Figure 5 is a sectional side view of the carriage-mechanism to illustrate the several features of improvement.

Figure 6 is a top plan view of the line-space-pawl-carrier and the line-space lever, and shows, partly sectioned, the novel cushioning element in the form of a shield applied to the nose of the line-space lever, and how said shield may yield in line-spacing operations.

Figure 7 is a perspective view of the nose-end of the line-space lever and the novel cushioning shield applied to said nose.

Figure 8 is a top plan view which shows the line-space lever and its novel cushioning shield when the parts are in normal position, and further shows the novel resilient stop-means, whereby the spring-urged return of the line-space-pawl carrier is quietly arrested. The view also brings out details relating to the novel case-shift stop-devices at the front of the platen-frame.

The improvements are illustrated as applied to typewriter-carriage mechanism, such as the Underwood.

A carriage-frame 11 runs upon a rear track 12 and a front track (not shown). A platen 13 is journaled in a frame 14, supported in said carriage-frame 11, for case-shifting movements, by means of side-arms 15 that are fastened to a cross-shaft 16 to work in unison, and are fulcrumed upon eccentrically adjustable studs 16^a retained in said carriage-frame 11. Said side-

arms 15 support the platen-frame 14 at gudgeons 18 of the latter, and side-links 19, connected to the carriage-frame 11, co-operate with said side-arms 15 to guide the platen-frame case-shift movements. The usual key-controlled case-shift rail and its frame are shown at 20, Figure 5, the shift-rail engaging a roller 21 of the platen-frame. Ears 17, extending laterally from the sides of the platen-frame, have novel cushioning elements, to be described later herein, to abut the carriage-frame at 17^a to determine the lower-case position of the platen-frame.

A feed-rack 22 on the carriage, a pinion 23, an escapement-wheel 24 and dogs 25, 26 co-operate to letter-feed the carriage upon actuation of a universal bar 27 by type-bars represented at 28, and having upper and lower case types 28^a, Figure 5, the usual carriage-feeding spring-motor not being shown. The limber-dog 25 of the escapement-device is mounted upon a pivot 29 of the usual dog-rocker 30 upon which the dog 26 is fixed. The universal bar 27 has a rearward extension which engages an adjustable screw-stud 31 of the dog-rocker to actuate the latter. For binding said screw-stud 31 in its adjusted position, its hole in the dog-rocker 30 is split by a kerf 32.

A line-space lever 35 is pivoted to the carriage-frame 11 at 36, and has a nose-arm 37 for driving a slide 38 carrying a line-space pawl 39, which upon a rearward stroke of the slide may engage a line-space wheel 40 which is connected to a platen-axle 41 and is engaged by a spring-pressed detent-arm 44. The pawl-carrier or slide 38 is slidably supported by a platen-frame side-member 42 and a lateral fin 43 thereof. A spring 45 retracts the slide 38 upon release of the line-space lever 35. The line-space lever, in its normal idle position, Figure 8, abuts a cushioning stop 46; while the normal idle position of the line-space-pawl slide 38 is determined by a novel stop-device which will be described later herein.

The novel devices which conduct to make operation of the carriage-mechanism quiet will now be described.

A resilient connection between the line-space lever 35 and the line-space-pawl slide 38 conduces to quiet non-jarring line-spacing operation, inasmuch as such connection takes up any play which may arise between these parts and produce rattling, and also cushions the reactions which occur between these parts as they are reciprocated at the line-spacing operation. Such resilient connection is feasible in the form of a shield 47, arranged to work as a yieldable interponent between the line-space-lever-nose-arm 37 and the companion face 49 of said slide 38. Said shield 47 may have ears 50, Figures 6, 7 and 8, by means of which it is retained upon said line-space-lever-nose-arm 37, and pivoted thereto, at 51, to permit movement of its slide-engaging portion 52 relative to said nose-arm, to take up play between the latter and the slide 38 and to yield in order to act as a cushioning device. A spring for spreading the slide-engaging portion 52 of the shield and the nose-arm 37 apart to prevent rattle-producing play between the latter and the slide 38, is afforded by a resilient tongue 53, which, as best seen in Figure 7, may be struck from the shield, so as to be integral therewith. The shield may be provided with an extension 54, in order that the spring-tongue 53 may be of sufficient length. Said extension 54 may also act, by abutment of its free end with the line-space lever, to limit the spreading apart of the portion 52 and

the line-space-lever-nose as when the line-space lever is handled separately from the machine, the shield 47 being incorporated with said line-space lever. The shield 47 may be inexpensively stamped from sheet-metal, preferably 5 spring-steel, of a thickness of, say, from .005 to .010 of an inch for the illustrated carriage-mechanism. The shield may, moreover, be shaped to conform substantially with the profile of the line-space-lever-nose-arm 37 as indicated, 10 and its upper and lower edges may be turned, toward the line-space-lever-nose-arm as at 55, to stiffen the shield. It will be understood that the spring-tongue 53 of the shield tends to spread the slide-engaging portion 52 from the line-space-lever-nose-arm 37 by its reaction against the latter. Figure 8 shows the line-space-mechanism parts in their normal positions, and furthermore indicates how the shield acts to prevent rattle-producing play between the line-space-lever-nose and the line-space-pawl-carrying slide 38. Figure 6 shows how the shield 47 has yielded, until its portion 52 abuts the line-space-lever-nose 37, in the line-space-lever stroke; it being evident that by its capability for 25 so yielding, the shield also conduces to preventing the reactions, between the line-space-pawl slide 38 and the line-space lever 35 during line-spacing, from producing noise and jarring effects.

The return of the line-space-pawl carrier or 30 slide 38 by its spring 45 is quietly arrested as follows. An element 56 has a branch which forms a leaf-spring 57 for urging the line-space pawl 39 toward the line-space wheel 40, said element being secured to said slide as at 58. Said element 56 is of resilient material, preferably 35 spring-steel, and the provision of another extension or branch 59 thereon, arranged to strike the slide-guiding fin 43, enables said element 56 to also serve for quietly arresting said return of the 40 slide 38. For this purpose, said extension 59 may be formed as shown, and its end may be bent as at 60, so that, by reason of the consequent offsetting of the point of impact, said extension will tend to flex and recover at its impact against the slide 45 guide or fin 43, which acts as a counter-stop, and thereby make said impact and the arresting of slide 38 quiet. By thus utilizing said pawl spring-forming element 56 a resilient stop-device is afforded at negligible extra cost. 50

The rearward stroke of the universal bar 27 rocks the dog-rocker 30 from the Figure 3 position to the Figure 4 position to permit spring-pressed escape of the limber-dog 25 preparatory to an ensuing carriage-feeding step. For quietly 55 arresting such escape, a novel dog-stop is provided, and may be easily adjusted to regulate the extent of escape of the limber-dog 25. Said stop may be arranged as follows. A stop-member 62 of spring sheet-material has a dog-arresting extremity 63 which is rendered resilient, for sound-deadening purpose, by extending from a body-part 64 by way of reflex bends, as indicated at 65, 66, Figures 3 and 4, said body-part 64 being mounted against the rear face of the dog-rocker 60 65 66. Means for adjustably securing said stop-member 62 to the dog-rocker 30 include only one binding screw 67, since the body-part 64 of said stop-piece may have bent therefrom an anchoring tongue 68 which by its disposition within 70 the dog-rocker kerf 32 co-operates with said binding screw 67 to hold said stop-member 62. Said tongue 68 may move along said kerf 32 for adjustment of the stop-member 62 in a direction which will be appropriate for effecting regulation 75

of the swing of the limber-dog 25, since a stop-face 70 of said dog is inclined to said kerf 32. Therefore, adjustment of the stop-piece 62 up or down as directed by said kerf will move its 5 dog-arresting extremity 63 from or toward said stop-face 70. A screw-hole 71, in the stop-member 62, for the binding screw 67 is elongated to permit such up-and-down adjustment of the stop-member, and the body-part 64 of the latter 10 may be arranged to space the binding screw 67 from the tongue 68, as shown in Figures 3 and 4. Adjustment of the stop-piece 62 involves loosening and tightening of only said one binding screw 67, and the latter is accessible from the back of 15 the machine.

For regulating the range of case-shift movement of the platen-frame 14, and for arresting said movement quietly the following devices are provided. Each platen-frame side-member 42 20 has a forwardly-extending horn 73 having a horizontal stop-edge 74 for abutting an oblong ferrule-like sound-deadening stop 75 made of resilient sheet-metal. A stop-supporting boss 76, at each side of the carriage-frame 11, has a horizontal slot 77 into which a lower side 78 of the stop is inserted and seated edgewise. An upper side 79 of the oblong resilient stop passes over and is spaced from the top of said boss 76, as at 80, Figure 5. Said sides 78, 79 of the resilient 25 stop 75 extend rearwardly, cantilever-wise, from said boss 76 for engagement with the platen-frame side-member 42, the edge 74 of the latter abutting the upper face or side 79 of the stop 75 in the lower-case platen position. A platen-frame-arresting portion 81 of the lower or boss-engaging side 78 of the stop 75 is inclined relatively to the boss-slot 77 and may be engaged by an edge 82 of the platen-frame side-member 42 30 to determine the upper-case platen position. The stop 75 is fastened in the supporting boss 76 by a headed clamp-screw 84 threaded into said boss, the clamping head of said screw bearing upon the outer edge of the lower side 78 of the stop 75, as indicated in Figure 2. Upon loosening said clamp-screw 84, the oblong stop 75 may 35 be adjusted endwise in the boss-slot 77, and, by reason of the inclination of the platen-frame-arresting portion 81 of said stop 75 relative to said slot 77, the latter extending perpendicularly to the direction of case-shift, such endwise adjustment of the stop 75 will effect adjustment of the upper-case platen position. It will be noted 40 that the relative arrangement of the platen-frame stop-edge 74, the upper ferrule side 79 and the boss-slot 77 is such that adjustment of the stop-ferrule 75 along said slot does not affect the lower-case platen position.

For preventing play, in case-shift direction, of the stop 75 in the boss-slot 77 and thereby enable 45 the stop, in any endwise adjusted position, to uniformly limit the case-shifts, a play-take-up screw 85 may be threaded into the boss 76 to keep the lower chord or side 78 of said stop 75 against the upper side of the slot 77, as indicated in Figures 2 and 5. Thus the sides of the boss-slot 77 may fit the ferrule loosely, thereby 50 conducting to reduce the cost of manufacture. Furthermore, the loose fitting slot 77 facilitates the described endwise ferrule-adjustment, it being understood that for this purpose the play-take-up screw 84 may be loosened and tightened at will. It will be understood that the clamp-screw 84 serves to prevent sidewise displacement of the stop 75.

75 Engagement of the platen-frame ears 17,

formed upon frame-members 91, with the carriage-frame at 17^a is cushioned for sound-deadening purpose by the following novel means arranged for application to the limited room afforded upon said ears. A thimble 92 rises from the upper surface of the ear 17, and may be fastened to the ear 17. A cushioning pad 93, seated within a counterbore 94, at the bottom of said thimble 92, may abut the carriage-frame at 17^a, said pad extending below the bottom surface of the ear 17. 10 A screw 96 has a head 97 engaging the bottom of the pad to retain the latter against the counterbored seat of the thimble, and extends upwardly through the pad and through the thimble, so that a nut 98, threaded upon said screw and drawn against the top of the thimble, will cooperate to retain the pad 93. By variably drawing upon the screw 96 by means of the readily accessible nut 98, the pad 93 may be variably compressed, and thereby its extension below the bottom of the ear 17 may be regulated to facilitate correspondence with the adjustment made at the front of the platen-frame to determine the lower-case platen-level. The ear 17 may also be bent up or down for adjustment of said platen- 25 level.

Plates 99, adjustably secured to the carriage-frame 11, by screws 100, present abutments 101 for supporting the cross-shaft 16 against flexing, thereby enabling the side-arms 15, fastened to 30 said shaft, to rigidly resist the endwise tending inertia of the platen and its frame 14, as each carriage-advance is checked.

Variations may be resorted to within the scope of the invention, and portions of the improvements may be used without others.

Having thus described my invention, I claim:

1. In typewriter-carriage mechanism arranged for quiet operation, said carriage-mechanism including a revoluble platen, and line-spacing devices, the combination with a reciprocatory line-space-ratchet-pawl carrier, and a line-space operating lever having an arm presenting a nose substantially against a companion face of said pawl-carrier for driving the latter, of an element 45 arranged to work resiliently between said line-space-lever-nose and the contiguous pawl-carrier face to prevent rattle-producing play therebetween, and to cushion the reactions occurring between said nose and pawl-carrier at the line- 50 spacing operation.

2. In typewriter-carriage mechanism arranged for quiet operation, said carriage-mechanism including a revoluble platen, and line-spacing devices, the combination with a reciprocatory line-space-ratchet-pawl carrier, and a line-space operating lever having an arm presenting a nose substantially against a companion face of said pawl-carrier for driving the latter, of a comparatively thin shield arranged to work resiliently 60 between said line-space-lever-nose and the contiguous pawl-carrier face to prevent rattle-producing play therebetween and to cushion the reactions occurring between said nose and pawl-carrier at the line-spacing operation. 65

3. In typewriter-carriage mechanism arranged for quiet operation, said carriage-mechanism including a revoluble platen, and line-spacing devices, the combination with a reciprocatory line-space-ratchet-pawl carrier, and a line-space operating lever having an arm presenting a nose substantially against a companion face of said pawl-carrier for driving the latter, of a comparatively thin shield arranged to work resiliently 70 between said line-space-lever-nose and the con- 75

tiguous pawl-carrier face to prevent rattle-producing play therebetween and to cushion the reactions occurring between said nose and pawl-carrier at the line-spacing operation, said thin shield being incorporated with the line-space lever, and being arranged to react resiliently against the latter and against said pawl-carrier face.

4. In typewriter-carriage mechanism arranged for quiet operation, said carriage-mechanism including a carriage-frame, a revolute platen, and line-spacing devices, the combination with a reciprocatory line-space-ratchet-pawl carrier mounted by a platen-frame which is supported for case-shifting movement relative to said carriage-frame, and a line-space operating lever mounted on the carriage-frame and having an arm presenting a nose substantially against a companion face of said pawl-carrier for driving the latter, irrespective of the case-shift, said face extending in case-shift direction, of an element arranged to work resiliently between said line-space-lever-nose and the contiguous pawl-carrier face to prevent rattle-producing play therebetween, and to cushion the reactions occurring between said nose and pawl-carrier at the line-spacing operations.

5. In typewriter-carriage mechanism arranged for quiet operation, said carriage-mechanism including a carriage-frame, a revolute platen, and line-spacing devices, the combination with a reciprocatory line-space-ratchet-pawl carrier mounted by a platen-frame which is supported for case-shifting movement relative to said carriage-frame, and a line-space operating lever mounted on the carriage-frame and having an arm presenting a nose substantially against a companion face of said pawl-carrier for driving the latter, irrespective of the case-shift, said face extending in case-shift direction, of a shield of comparatively thin spring-material arranged to resiliently work between said line-space-lever-

nose and the contiguous pawl-carrier face, said shield being pivoted relatively to the line-space lever and having a tongue serving as a spring reacting against said line-space lever, whereby said shield is kept resiliently pressed against said pawl-carrier face to prevent rattle-producing play between the latter and the line-space-lever-nose, and to cushion the reactions occurring between said nose and the pawl-carrier at the line-spacing operations.

6. In typewriter-carriage mechanism arranged for quiet operation, said mechanism including a revolute platen and line-spacing devices therefor, the combination with a reciprocatory line-space-ratchet-pawl carrier, and a spring for returning said pawl-carrier after its line-space stroke, of an element made of sheet spring-material and mounted upon said pawl-carrier, said element being arranged to act as a leaf-spring bearing upon the line-space-ratchet-pawl on said carrier, said element being further arranged to also act as a resilient stop, engageable with a counter-stop, for quietly arresting the spring-pressed return of said pawl-carrier.

7. In typewriter-carriage mechanism arranged for quiet operation, said mechanism including a revolute platen and line-spacing devices therefor, the combination with a line-space-ratchet-pawl carrier, spaced guides slidably mounting said pawl-carrier for reciprocation, and a spring for returning said pawl-carrier after its line-space stroke, of an element made of spring-material and mounted upon said pawl-carrier, said element having a branch acting as a leaf-spring bearing upon the line-space-ratchet-pawl on said carrier, said element having another branch to serve as a resilient pawl-carrier stop for which one of said spaced guides serves as a counter-stop, whereby a resilient stop-device for quietly arresting the spring-pressed return of said pawl-carrier is afforded at negligible cost.

WILLIAM F. HELMOND.
